(57) **CLAIM**

The ornamental design for an endoscope, as shown and described.

DESCRIPTION

FIG. 1 is a front perspective view of an endoscope in accordance with the new design;

FIG. 2 is a left side view thereof;

FIG. 3 is a right side view thereof;

FIG. 4 is a bottom view thereof;

FIG. 5 is a top view thereof;

FIG. 6 is a front view thereof; and,

FIG. 7 is a rear view thereof.

The center shaft portion of an endoscope in FIGS. 1–5 is shown broken away to show indeterminate length and for ease of illustration.

The broken line showing the front end portion of FIGS. 4 and 6 is for the purpose of illustrating environmental structure and forms no part of the claimed design.
